FIG.15

FIG.16

FIG. 1 is a perspective view of a calculating machine embodying my new design;

FIG. 2 is a top plan view of the calculating machine shown in FIG. 1;

FIG. 3 is a left side elevational view;

FIG. 4 is a right side elevational view;

FIG. 5 is a rear elevational view;

FIG. 6 is a front elevational view;

FIG. 7 is a bottom plan view;

FIG. 8 is a perspective view, with the glass hood of the display panel opened;

FIG. 9 is a perspective view of another embodiment of the calculating machine shown in FIG. 1 wherein the rear body portion thereof has been foreshortened;

FIG. 10 is a top plan view of the calculating machine shown in FIG. 9;

FIG. 11 is a left side elevational view thereof;

FIG. 12 is a right side elevational view thereof;

FIG. 13 is a rear elevational view thereof;

FIG. 14 is a front elevational view thereof;

FIG. 15 is a bottom plan view thereof; and

FIG. 16 is a perspective view thereof, with the glass hood of the display panel opened.

I claim:

The ornamental design for a calculating machine, as shown and described.
